UNITED STATES PATENT OFFICE.

WILLIAM HORSFALL GREENWOOD AND FREDERICK FARRAR, OF BRADFORD, COUNTY OF YORK, ENGLAND.

APPLIANCE FOR PREVENTING UNEQUAL WEAR OF LEATHERS OF DRAWING-OFF ROLLERS OF COMBING-MACHINES.

SPECIFICATION forming part of Letters Patent No. 373,890, dated November 29, 1887.

Application filed June 25, 1886. Serial No. 206,266. (No model.) Patented in England July 27, 1885, No. 9,009.

To all whom it may concern:

Be it known that we, WILLIAM HORSFALL GREENWOOD and FREDERICK FARRAR, both of Bradford, in the county of York, England, have invented an Improvement in Appliances for Preventing Unequal Wear of Leathers of Drawing-Off Rollers of Combing-Machines, of which the following is a full, clear, and exact description.

10 Our invention consists in an improved device for regulating the speed of the traverse of the leathers of the drawing-off rollers of the "Nobles" and other combing-machines in which such leathers are traversed by means of 15 eccentrics fitted on a cross-shaft under the revolving circular rack, which eccentrics impart a reciprocating motion to the slide-brackets carrying the runners or guides for the leathers. Hitherto the eccentrics have been driven at a 20 regular speed, generally by means of a ratchet-wheel fixed on the end of the eccentric-shaft, the pawl which drives it being mounted on one end of an L-shaped lever, the other arm of which is actuated by projections on the under side of the flange of the circular revolving rack. Thus an irregular stroke or traverse was communicated to the slide-brackets as they attained a maximum speed when the eccentrics were at half-stroke and a minimum speed 25 at the commencement and termination of each stroke. This irregularity of the stroke of the slide-brackets and corresponding irregularity in the traverse of the leathers caused such leathers to wear unequally, and therefore work imperfectly. By our improvements we impart a more regular stroke to the slide-brackets, and consequently a more perfect or regular 30 traverse is imparted to the leathers, which are therefore more evenly worn and maintained in 35 working order considerably longer than heretofore.

In the drawings, Figure 1 is a plan of the circular revolving rack, the steam-chest, and slide-brackets of a Nobles combing-machine, 40 together with the ordinary mechanism for actuating such slide-brackets in conjunction with our improvements. Fig. 2 is a side elevation, and Fig. 3 is a sectional elevation of the same. Fig. 4 is a partial sectional elevation, and Fig.

5 is a partial side elevation, of the ordinary means for shifting the leathers. Fig. 6 is a side elevation of our improved arrangement with the circular rack in section.

Hitherto the eccentrics *k* have been driven at a regular speed by means of a ratchet-wheel, 55 1, Figs. 4 and 5, fixed on the end of the eccentric-shaft *a*, the pawl 3, which drives it, being mounted on one arm of an L-shaped lever, 4, the other arm, 5, of which is actuated by projections *h* on the under side of the flange 60 7 of the circular revolving rack *j*. Thus an irregular stroke or traverse is communicated to the slide-brackets *l* as they attain a maximum speed when the eccentrics *k* are at half-stroke and a minimum speed at the commencement 65 and termination of each stroke. This irregularity in the stroke of the slide-brackets *l* and corresponding irregularity in the traverse of the leathers 11 causes such leathers to wear unequally, and therefore to work imperfectly. The revolving circular rack *j* is below the comb-circles *o*, as shown in Figs. 4 and 6.

To carry out our invention, we fix on the eccentric-shaft *a*, at the opposite end to the ratchet-wheel *b*, by means of which the shaft 75 is rotated, a metallic disk, *c*, opposite segments of the periphery of which are cut with ratchet-teeth *d*. At the side of the disk *c* a pendent lever, *e*, is mounted on the bracket *f*, fixed to the steam-chest *g*. The inclined adjustable 80 tappets or projections *h* are bolted to the under side of the flange of the revolving circular rack *j*, and they come alternately in contact with the top of and impart an oscillating motion to the pendent lever *e*, and the pawl *l*, 85 mounted thereon, receives a reciprocating motion. Thus, as the disk *c* revolves each time the eccentrics *k* approach the end of their stroke and the slide-brackets *l* their minimum speed, the pawl *l* engages with and gears into 90 the teeth *d* and gives an additional movement, so as to accelerate the speed of the disk *c*, the shaft *a*, and the eccentrics *k*, and therefore accelerates the speed of the slide-brackets *l*, carrying the runners or guides for the 95 leathers 11, and thereby communicating a more regular traverse to such leathers. Each tappet *h* is secured to the under side of the

flange of the circular rack *j* by a bolt, 12, and several bolt-holes are provided for said bolt, as shown in Fig. 1, to allow for properly placing said tappet *h*.

5 We claim as our invention—

The combination, with the drawing-off rolls and leathers in a combing-machine, of the shaft *a*, a ratchet-wheel, *b*, at one end, a pawl by which a progressive rotation is given, eccentrics *k*, brackets *l*, runners or guides upon said brackets, the disk *c* upon said shaft *a*

and having segments of teeth on opposite sides, the lever *e* and pawl *l*, the bracket *f*, to which the lever *e* is pivoted, the circular rack *j*, and the tappets *h*, secured to the flange of said rack, substantially as and for the purposes set forth. 15

WILLIAM HORSFALL GREENWOOD,
FREDERICK FARRAR.
